APPARATUS FOR MAKING STRIP WOUND
MAGNETIC CORESJohn C. Granfield, Pittsfield, Mass., assignor to
General Electric Company, a corporation of
New York

Application January 30, 1937, Serial No. 123,250

10 Claims. (Cl. 242—4)

In my copending application, Serial No. 123,249, filed concurrently herewith, I have disclosed and claimed certain improvements in electro-magnetic induction apparatus such as transformers and reactors, and the method of making the same, and I have disclosed but not claimed therein in the machine for making such apparatus, such machine constituting subject matter claimed in the present application. This application, like 5 the application filed concurrently herewith, is a continuation-in-part of my application, Serial 10 No. 77,499, filed May 2, 1936.

My invention relates particularly to a machine for applying strip wound magnetic cores to transformers, reactors and the like. In accordance with the method disclosed in my copending applications the strip wound core is adapted to be applied to form wound conductive winding structures. My machine is adapted to apply strip 20 of various composition and thickness. One kind of strip which may be very easily applied by my machine is strip of high reduction cold-rolled silicon steel containing about 3% silicon. This strip may be obtained from the mill in long 25 lengths and long lengths may also be made by welding shorter strips end to end. In accordance with the method disclosed in my applications, the strip is wound spirally to form a hollow cylinder containing the exact amount of 30 magnetic material required for one of the spirally wound core elements of a transformer. The inside and outside dimensions of the tightly wound coil of strip are made exactly the same as the dimensions that the completed core element is to 35 have in the transformer. After such a coil of strip has been wound the end of the outside turn of the strip is secured to the next underlying turn of strip, preferably by tack welding it thereto, and the coil of magnetic strip in this form 40 is placed in a heat treating oven which gives the coil of strip a permanent set. The high reduction, cold-rolled silicon strip has the most favorable magnetic orientation of the grain in the direction in which the strip has been rolled. 45

The heat treatment of such a coil of strip for at least an hour at a temperature of about 800° C. to about 900° C. in the heat treating oven assists in developing the favorable magnetic characteristics of the strip as well as giving it a permanent set. The coil of strip, after it has been taken from the heat treating oven and cooled; is then wound through the window of the conductive winding structure by loosening the tack weld at the outer end of the strip, carrying the 50 outer end of the strip through the window to

form a loop having a circumference considerably greater than the outside circumference of the heat treated coil. The end of the strip of the large loop is secured to the next underlying turn of the strip whereupon, by rotation of the 5 heat treated coil together with the large loop, the strip is unwound from the heat treated coil and wound on the inside of the large loop. After all of the strip has been coiled into the larger 10 loop the tack weld is loosened and the larger 10 loop collapsed upon the leg of the conductive winding structure, and in the completed core element the coil of strip has the exact dimensions that it had when heat treated. In accordance with such method of application, the 15 strip can be applied so that when the core element has been completed it is free from elastic strains which would impair its magnetic qualities.

My invention will be better understood from the following description taken in connection 20 with the accompanying drawings in which Figs. 1 and 2 show an early step in the application of a coil of magnetic strip to a transformer, the figures being alike except that they show different constructions of the transformer conductive windings; Fig. 3 shows an intermediate step of the operation; Fig. 4 shows a later step in the operation, and Fig. 5 shows the final step in the operation of winding the strip on to the transformer; Fig. 6 shows in perspective with parts 25 broken away, one form of machine embodying my invention; Fig. 7 is a view taken generally from the left of Fig. 6 showing parts of the machine; Fig. 8 is a perspective view showing certain 30 elements of the machine; Fig. 9 is a view showing a part of the machine of Fig. 6; and Fig. 10 shows a detail of one of the elements of the machine.

Referring to Fig. 1, a transformer conductive winding structure to which a coil of magnetic 40 strip is to be applied is shown in cross-section. The winding structure shown in Fig. 1 is of the general type shown in perspective in Fig. 6. This transformer comprises for example a primary winding 10 and two secondary windings 11 and 12 located concentrically with the primary winding, the windings 11 and 12 being respectively outside and inside of the winding 10. The window through which the strip is to be carried 45 and wound about the right-hand leg of Fig. 1 is indicated at 13. The sides of the winding structure or winding legs as they may be called are each provided with suitable insulation having 50 circular contour, such insulation being in- 55

dicated at 14. The coil of magnetic strip to be applied is shown at 15.

In the stage of operation shown in Fig. 1 the end of the coil of strip has been carried through the window 13 in the direction of the long arrow and curved into the form of a large loop 16 and secured to the next underlying turn of strip, as for example by tack-welding, at 17. In my machine the coil of strip 15 is placed over a roller 18 engaging the inside of the coil, and a roller 19 is provided to engage the outside of the coil. As hereinafter described, means are provided for biasing the roller 18 toward the roller 19 so that the coil of strip is gripped between these rollers which are provided with surfaces of rubber or the like to reduce slipping. The rollers 18 and 19 are driven simultaneously and in opposite directions, as indicated by the arrows shown on the rollers in the drawing. The rotation of the rollers turns the coil of strip 15 and turns the large loop 16 to unwind the coil of strip 15 and simultaneously rewind the strip into the larger loop 16, turns of strip being successively added to the inside of the loop 16. To facilitate threading the strip through the window 13 and for another purpose hereinafter described, a guide plate 20 is provided. For a generally similar purpose, a roller 21 is provided to bear against the outside of the loop 16. To prevent any tendency of the strip to climb up between the rollers 18 and 19 during the winding operation, a roller 22 is provided bearing on the top edge of the coil 15 and the top edge of the larger loop 16.

The showing of Fig. 2 differs from Fig. 1 only in that the arrangement of the winding structure of the transformer to which the coil of strip is to be applied is somewhat different. In Fig. 2, the secondary windings 11' and 12' are located one on each side of the primary winding 10' instead of concentrically on the inside and outside of the primary winding. Both winding structures illustrated give a substantially cruciform cross-section to the winding leg, the periphery having a stepped form approximating a circle.

Fig. 3 shows a stage in the operation where nearly all of the strip has been unwound from the coil 15 and rewound into the large loop 16. It will be observed that the number of layers of strip in the larger loop 16 is only about half as great as the number of layers originally in the coil 15. The inside of the larger loop turns freely through the window 13 even though a number of layers of strip have been placed within the outside turn of the loop 16. When the stage of operation shown in Fig. 3 is reached, a little further rotation of the rollers 18 and 19 releases the inside end of the strip which tends to curl around the insulating cylinder 14. The operator may catch the end of the strip by hand and hook it over the insulating cylinder 14 if it should fail to assume that position. The operator then removes the roller 18 and loosens up the tack weld 17 which he may do by a screw driver or other implement. The large loop, by reason of the resiliency of the strip and its tendency to assume the position it occupied when heat treated, collapses to the general position shown in Fig. 4. The strip would assume a still more closed form if it were not for the friction of the edge of the strip upon the table upon which the winding operation is carried out.

The operator then secures the inside end of the strip to the insulating cylinder 14 which he may conveniently do by clamping it by a small clamp. He then brings the oppositely rotating

rollers 23 and 24 into contact with the outside of the loop 16 to collapse or close up the loop. Fig. 4 shows these rollers just touching the outer surface of the loop. When the operator presses these rollers 23 and 24 toward each other, the loop 16 may move to assume a somewhat elliptical shape but any substantial movement is limited by the guide plate 20. The loop 16, by the rotation of the rollers 23 and 24, is rapidly collapsed and the side of the loop touches the guide plate 20 only during the first few revolutions of the loop. The collapsing loop is followed up by the inward movement of the rollers 23 and 24 and in a very short time the loop is collapsed to its completed form as shown in Fig. 15 at 25. The collapsing of the loop is assisted by the permanent set given the strip in the heat treating oven and since the outside diameter of the cylinder of insulation 14 was made exactly the same as the inside diameter of the heat treated coil 15, the completed coil of strip 25 remains in the completed position after the rollers 23 and 24 are removed. The outside end of the strip may then be tack welded to the next underlying turn of strip at 26. The turns of strip in the completed coil 25 are in the same sequence that they were in the heat treated coil 15. In accordance with the method of applying the strip, it has not been strained beyond the elastic limit and the completed magnetic core is free from strains which would impair its permeability or watt loss characteristics.

Referring to Fig. 6, a completed transformer is shown in which two cores 26 and 27 of magnetic strip have been applied to a winding structure. The tack-welds securing the outer end of the strip of the core 26 are indicated at 28. The transformer is ready to be lifted out of the machine preparatory to inserting a new winding structure to which magnetic cores are to be applied. The rollers 18 and 19 described in connection with Figs. 1 and 3 are shown in Fig. 8, the roller 19 also being shown in Fig. 6. The guide roller 21 heretofore referred to for guiding the side of the large loop of strip is shown in Fig. 6 mounted on a member 29 adapted to be adjusted along the table 30 and clamped in any adjusted position by a wing nut 31. The roller 22 heretofore referred to which bears on top of the strip is shown in Fig. 9 as mounted on a standard 32 vertically and rotatably adjustable in a support 33, also shown in Fig. 6. The standard may be clamped by the set screw 34 to hold the roller 22 in any position to which it has been adjusted. The rollers 23 and 24 for collapsing the strip from the position shown in Fig. 4 to that shown in Fig. 5 are shown in Fig. 6 as mounted so that they may be swung toward and away from each other.

Before describing in greater detail the means for operating the various rollers, it will be helpful to describe how the winding structure to which the magnetic cores are to be applied is mounted on the machine and moved to the proper position for application of the strip cores. In the machine shown in Fig. 6, the transformer is clamped between four lower rollers 35 and four upper rollers 36. These rollers are preferably provided with a surface such as rubber so that they will not damage the transformer windings. The four lower rollers are mounted on a plate 37 pivotally supported as hereinafter described and the upper rollers 36 are mounted on a plate 38 which is pivotally mounted on a threaded rod 39 adjustable by a hand-wheel 40. The rod 39 is threaded

through a forwardly projecting portion 41 of a supporting member 42 which has a lower forwardly projecting portion 43 upon which the lower plate 37 carrying the lower clamping rollers 38 is pivotally mounted.

For simplicity in description I shall refer to the supporting member 42 with the parts mounted on the upper and lower projecting portions 41 and 43 as the winding head. In the stage of operation shown in Fig. 6 the transformer has been finished. To release it the operator turns the hand wheel 40 to lift the upper clamping rollers 36 out of engagement with the transformer windings. The transformer is then lifted out of the machine and another transformer winding structure to which magnetic cores are to be applied is placed so as to be supported by the lower rollers 35. The hand wheel 40 is then turned to lower the plate 38 carrying the upper rollers 36 to clamp the winding structure in place between the upper and lower rollers. The upper plate 38 is prevented from rotation when the rod 39 is rotated by the hand wheel 40, by a slidable rod 44 which carries a projection entering an opening in the member 38. There is an opening 45 in each end of this member. By raising the rod 44 sufficiently to lift the projection out of one of the openings 45 in the plate, the winding structure may be rotated upon the pivotal mountings of the plates 37 and 38 through 180°, and it may be held in its new position by the entrance of the projection on rod 44 into the other opening 45.

After the winding structure has been mounted in the winding head as described it must be moved down into the table 30 a sufficient distance to bring the point on the winding structure where the bottom edge of the strip core is to be placed even with the surface of the table 30. To permit this vertical movement the supporting member 42 of the winding head is arranged to be moved vertically on a support 46 which may be clamped in position on the table 30 as hereinafter described. Guiding rollers 47 mounted on the supporting member 42 engage the side edges of the support 46 and rollers 48 mounted on the forwardly projecting member 41 bear on the back of the support 46. A rack 49 is welded to the edge of the supporting member 42 and a pinion 50 operated by hand wheel 51 engages this rack to move the member 42 along the supporting member 46. The shaft for the pinion 50 and hand wheel 51 is mounted at the top of a support 52 secured to a member 117 adapted to slide along and be clamped to the table 30 as hereinafter described. A clamping member 53 threaded into the member 42 and moving in a slot 54 in the member 46 is provided to clamp the member 42 to the member 46 in any adjusted position. When the operator wishes to lower the winding head, he loosens the clamping member 53 and operates a lever 55 to move a dog 56 away from the rack whereupon he can turn the hand wheel and lower the winding head into the table to the desired position. The lever 55 is operated to engage the dog 56 with the rack 48 and the operator then clamps the members 42 and 46 together by the clamping member 53.

After having lowered the winding head to bring the conductive winding structure of the transformer into the proper position with respect to the top of the table 30, the operator lays the heat-treated coil of magnetic strip to be applied to the transformer upon the table top and inserts the roller 18 into the coil. To permit the roller 18 to be inserted and removed, it is provided with a

projection 57 which enters a driving socket 58 rotatably mounted in a member 59, as shown in Fig. 8. The roller is provided with a collar 60 entering the socket 58. The edges of the socket are slotted and a pin 61 through the collar 60 enters the slots in the socket to provide a driving connection between the member 58 and the roller 18. The top of the socket 58 appears in Fig. 6. To enable the roller 18 to be inserted in the coil of strip placed on the table, it is necessary to move the socketed member 58 away from the roller 19. To enable this to be done, the member 59 in which the socketed member 58 rotates is mounted on rods 62 and 63 sliding in bearings in the table 30. The outer ends of these rods are connected by a crosspiece 64. This cross-piece 64 has an opening through which a guide pin 65 mounted on a member 66 secured to the table 30 projects so that the pin 65 guides the cross-piece 64, preventing the rods 62 and 63 from binding in the bearings of the table 30. Springs 67 and 68 are provided on the rods 62 and 63 between the table 30 and the cross-piece 64 to bias the roller 18 toward the roller 19 by biasing the member 58 carrying the driving socket 58 toward the right in Fig. 6. To move the socket 58 away from the roller 19 to permit the insertion of the roller 18, the operator raises a lever 69 which moves the outer end of a crank 70 downwardly. The outer end of this crank is secured to a cable or chain 71 passing over a pulley 72 and secured to the cross-piece 64. Raising the lever 69 therefore moves the cross-piece 64 and rods 62 and 63 to the left in Fig. 6, thus moving the supporting member 59 carrying the socket member 58 to the left. A pawl 73 is moved into engagement with teeth 74 on a member on the shaft of the lever 69 and crank 70 to hold the socket 58 in the position to which it has been moved against the bias of the springs 67 and 68.

After the operator has placed the roller 18 in position in the coil of strip and threaded the strip through the window in the winding structure and formed the large loop 16, as described in connection with Figs. 1 and 3, and has tack-welded the end of the strip, as there described, he raises the lever 69 slightly, releases the pawl 73 and permits the springs 67 and 68 to move the roller 18 toward the right in Fig. 6 to clamp the coil of strip between the rollers 18 and 19, as described in connection with Figs. 1 and 3.

The rollers 18 and 19 are now rotated to unwind the strip from the coil and wind it into the larger loop as described in connection with Figs. 1 and 2. The roller 19 is mounted in a bearing 55 in the table 30 and is driven by a pinion 75 which is in turn driven by a gear 76 as shown in Fig. 8. The gear 76 is mounted at the top of a shaft 77 which in the machine shown in Fig. 6 is driven through bevel gears 78 by a motor 79 operating 60 through pulleys and a belt 80 and a friction clutch 81. The clutch is a shifting clutch controlled by a foot lever 82.

The roller 18 as shown more clearly in Fig. 8 is driven by the pinion 72 through gears 83 and 84, the gear 84 engaging a gear 85 at the lower end of the socketed member 58 turning in the member 59. The axis of the gear 83 is fixed to the table 30. The gear 84 is floatingly mounted to permit horizontal movement of the gear 85 when the member 59 is shifted to move the position of the socket 58 as heretofore described. To permit of this floating movement the gear 84 is mounted between links which are pivoted respectively on the axes of the gears 83 and 84, 75

the upper two links being shown at 86 and 87 in Fig. 8. Before starting the rotation of the rollers 18 and 19 for the strip winding operation, the operator places the roller 22 in place to bear on the upper edges of the strip as heretofore described in connection with Figs. 1 and 3.

When the coil of strip has been unwound into the larger loop just beyond the position shown in Fig. 3, the operator stops the rotation of the rollers 18 and 19 and removes the roller 18, whereupon the strip takes the position shown in Fig. 4. The operator then breaks the tack weld securing the outer end of the strip to the next underlying strip, secures the end of the inside turn to the insulating cylinder 14 as heretofore described, and brings the rollers 23 and 24 into position to collapse the strip. To bring the rollers 23 and 24 into this position, the operator moves the lever 88 which through the link 89 and a link which does not appear in Fig. 6 turns the member 90 pivoted at its center at 91. The ends of the member 90 are connected through members 92 and 93 to members which swing the rollers 23 and 24 into and out of position. These rollers 23 and 24 are mounted at the outer ends of arms 94 and 95 pivoted at the back of the machine, the pivot point for the arm 94 being shown at 86. The members 92 and 93 operated from the lever 88 as heretofore described, swing the arms 94 and 95 about their pivot points. The connection between the member 92 and the arm 94 is indicated at 97, the member 97 being rigidly secured to the lower member of the arm 94. This lower member of the arm 94 does not appear in Fig. 6 but the lower member of the arm 95 is shown in Fig. 6.

To rotate the rollers 23 and 24, belts 98 and 99 are provided operating over pulleys. The driving pulleys are mounted on the axes of the pivoted arms and driven through suitable gear mechanism.

The gear mechanism for driving the pulleys on the arm 94 consists of a pair of bevel gears 100 and a pair of bevel gears 101 driven from a pinion 102 on the shaft 103. The pinion 102 is driven from a bevel gear 104 on the shaft 77, as shown in Fig. 8. Similar gearing mechanism is provided for driving the roller 23, but the gears do not appear in the drawings except that a pinion 105 on the driving shaft 106 and engaging the gear 104 does appear in Fig. 8.

The strip being in the position shown in Fig. 4 and the rollers 23 and 24 moved against the strip, as shown in Fig. 4, the rotation of the rollers collapses the strip to its completed position shown in Fig. 5, as heretofore described. To follow up the collapsing loop, the operator continues to move the lever 88 to swing the arms 94 and 95 inwardly. To provide a gentle and yielding engagement of the rollers 23 and 24 with the loop of strip, the members 92 and 93 are preferably constructed as shown in Fig. 10. These members comprise a cylinder 107 in which a plunger 108 moves. A spring 109 is provided tending to move the plunger out of the cylinder. The construction provides a kind of yielding dash-pot connection. The relative motion of the plunger and the cylinder is limited by a pin 110 through the plunger which moves in slots 111 in the cylinder.

To fill partially the opening in the table top and prevent the strip, or any part of it, from moving into the opening during the handling and winding operation, a member 112 is mounted on ledges in the opening in the table top which

opening is made relatively large to permit various sizes of winding structures to be lowered into and raised from the table and to permit longitudinal movement of the socket member 58. The member 112 is merely laid in place at the proper time and the proper position of this member, where a number of coils of the same size are to be wound, may be readily ensured by an adjustable stud locked in adjusted position by a nut 113.

After the operator has completed the winding of one of the magnetic cores upon the transformer, he lifts the winding head by operating the hand-wheel 51, as heretofore described. The winding head is secured in its upper position by 15 the dog 56 engaging the rack 49, whereupon the operator lifts the rod 44 and turns the winding structure through 180 degrees, as heretofore described, at which position the rod 44 engages the opening in the other end of the member 38. The 20 operator then lowers the winding head to the proper position and proceeds to apply the other core to the winding structure in the manner heretofore described.

To accommodate various sizes of winding structures and to adjust the distance between the winding structure and the rollers 18 and 19 for various diameters of the large loop 16, the winding head is made bodily movable longitudinally of the table. To accomplish this forward and 30 backward movement, a hand-wheel 114 is provided which operates pinion 115 engaging a rack 116 secured to the member 117 which slides on the table top 30 as is more clearly shown in Fig. 7. To clamp the winding head to the table in any 35 adjusted position a member 118 is provided which extends through the lower part of the support 48 and is threaded into a plate 119 bearing on the bottom surface of the table top. When the member 118 is tightened, the table top is clamped between the members 117 and 119. Since the transformer mounted in the winding head is heavy and since all of its weight is in front of the winding head, the winding head tends to tip forwardly which tendency would cause the members 117 and 45 119 to bind on the table top interfering with free longitudinal adjustment of the winding head. To overcome this tendency a member 120 is bolted or otherwise secured to the member 117 and this member 120 has two forwardly projecting members one of which is shown at 121. At the forward ends of these members 121 rollers are mounted, one of which is shown at 122 in Fig. 6. These rollers bear upon tracks on the supporting plate 124. One of the tracks is shown at 123. The 55 supporting plate 124 also supports various parts of the mechanism heretofore described including table 30.

While I have shown a particular construction of machine which I have found well adapted for 60 the purpose described, it will be apparent to those skilled in the art that many changes and modifications may be made without departing from the spirit and scope of my invention and I therefore aim in the appended claims to cover all such 65 changes and modifications.

What I claim as new and desire to secure by Letters Patent of the United States is:

1. A machine for applying strip wound magnetic cores to winding structures comprising 70 means for holding the winding structure in position to be wound, means for supporting a coil of magnetic strip, said means being spaced away from the winding structure a sufficient distance to permit a relatively large loop of strip from said 75

- coil to be threaded through said winding structure, said means comprising oppositely rotating rollers engaging the inside and outside of the coil of strip to rotate the coil and drive the strip to 5 unwind the coil and rewind the strip material into the larger loop, and means for biasing the oppositely rotating rollers toward each other to grip the turns of strip located between the rollers.
2. A machine as set forth in claim 1 comprising means for collapsing the turns of the large loop upon the winding structure.
3. A machine as set forth in claim 1 including means for engaging the edge of the strip to prevent movement of the strip along the rollers which 15 drive the strip.
4. A machine of the class described comprising means for unwinding a flatwise spirally wound coil of strip and simultaneously rewinding it into a larger coil around an object out-side the original coil comprising oppositely driven rollers engaging the inside and outside of the coil, power driven rollers for collapsing the larger coil, and means for moving the coil-collapsing rollers inwardly as the coil collapses.
- 25 5. A machine for assembling a winding and a magnetic core of the wound type, said machine including means for supporting the winding, means comprising a rotatable roller for supporting a wound coil of magnetic strip with its axis 30 parallel to one side of the winding means for pressing the coil of strip against said roller, and means for rotating said roller to unwind said coil and simultaneously rewind it around one side of the winding.
- 35 6. A machine for assembling a winding and a magnetic core of the wound type, said machine comprising means for supporting the winding and means comprising a roller for supporting a coil of magnetic strip material, a second roller 10 movable toward and away from the first roller, means for biasing said rollers toward each other to grip the coil of strip therebetween, and means for rotating one of said rollers to unwind said coil and simultaneously rewind it around one side 45 of the winding.
7. A machine for assembling a winding and a magnetic core of the wound type, said machine comprising means for supporting the winding at a given position, means for supporting a wound coil of magnetic material beside said position, means for rotating said coil to unwind it into a loop around one side of the winding and means for guiding said loop. 5
8. A machine for assembling a winding and a magnetic core of the wound type comprising a supporting table, a roller mounted for rotation on said table, a second roller biased toward the first roller, means arranged to move said roller against its bias to separate the rollers, said second roller being removably mounted to permit a coil of magnetic strip to be placed on the table and the roller thereafter inserted into the coil, said rollers being geared together to rotate in opposite directions and means for rotating the rollers to unwind said coil and simultaneously wind it around one side 15 of the winding.
9. A machine for assembling a winding and a magnetic core of the wound type comprising means for winding a strip of magnetic material into a relatively large loop turning freely through 25 the winding and means for collapsing the turns of the large loop about the winding comprising power driven rollers and means for swinging said rollers into and out of engagement with the turns to be collapsed, said means including yielding 30 means to permit of yielding engagement between said rollers and the sides of the loop.
10. A machine for assembling a winding and a magnetic core of the wound type comprising a supporting table, a winding head and means for 35 adjusting the winding head vertically with respect to the table, means for pivotally mounting the winding in the winding head and securing it in adjusted pivotal positions, means rotatably mounted on the table for rotating a strip of magnetic material through the winding and means for adjusting the winding head longitudinally of the table to vary the distance between the winding and said rotatable means. 40

JOHN C. GRANFIELD. 45
